UNITED STATES PATENT OFFICE.

CLINTON S. SHUGART, OF FAIRMOUNT, INDIANA.

KNOCKDOWN BARREL.

No. 880,926.

Specification of Letters Patent.

Patented March 3, 1908.

Application filed March 29, 1907. Serial No. 365,378.

To all whom it may concern:

Be it known that I, CLINTON S. SHUGART, a citizen of the United States, residing at Fairmount, in the county of Grant and State of Indiana, have invented new and useful Improvements in Knockdown Barrels, of which the following is a specification.

This invention relates to a knockdown barrel or other receptacle, and relates more particularly to a locking device for connecting the ends of the wire hoop or other binding element.

The invention has for one of its objects to improve and simplify the construction of devices of the character referred to so as to be comparatively easy and inexpensive to manufacture and whereby the ends of the wire hoops or equivalent members can be easily locked and unlocked for setting up or knocking down the barrel.

A further object of the invention is the provision of a locking member for connecting the looped ends of the binding wire or hoop together, one corner of the member being bent laterally to engage the wire for holding the member in locked position, the wire itself operating on the locking member to hold the hooked shaped corner in locking engagement.

With these objects in view and others, as will appear in the description proceeds, the invention comprises the various novel features of construction and arrangement of parts which will be more fully described hereinafter and set forth with particularity in the claims appended hereto.

In the accompanying drawing, which illustrates one of the embodiments of the invention, Figure 1 is a perspective view of a barrel to which the improved locking members are applied. Fig. 2 is an enlarged front view of one of the members showing it in locking position. Fig. 3 is a similar view showing the locking member in open position.

Similar reference characters are employed to designate corresponding parts throughout the several views.

In the present instance, I have elected to illustrate the invention in connection with a knockdown barrel, but it is obvious that it may be used on other containers or receptacles which are employed for shipping products to market and adapted to be knocked down so as to be conveniently packed for returning to the producer.

Referring to the drawing, 1 designates the staves of the barrel that are secured by staples 2 to the binding wires or hoops 3, the ends of the barrel being closed by heads 4. Each wire 3 has its ends formed into loops 5 and 6 for connection with the locking device 7. The locking device comprises a flat piece of sheet metal having one of its long edges adjacent one corner bent laterally to form an integral hook 8 for the purpose hereinafter to appear. At the corner of the locking member 7 diametrically opposite from the hook 8 is provided an aperture 9 for receiving the loop 5, whereby the locking member is hingedly and permanently connected with the wire 3. On the end of the member 7 opposite from that having the hook 8 is a hooked shaped lug 10 for receiving the loop 6.

When the locking member is in open position, the loops 5 and 6 will be approximately directly in line with each other with the length of the member disposed at right angles to the wire. After the loop 6 is hooked to the locking device, as shown in Fig. 3, the said device is swung upwardly around the loop 5 as a center, thereby exerting a draft on the wire 3 by drawing the ends thereof together. This throws the outer end of the member 7 into line with the end of the wire having the loop 6, and by engaging the wire under the hook 8, the locking device is prevented from swinging open under the tension on the wire. It will be noted that the loop 6 is considerably shorter than the length of the member 7 and the inner end of the loop or the coiled part 10' is adapted to bear on the edge of the member having the hooks 8 and 10, thereby tending to urge the member downwardly so that the hook 8 will be positively held in engagement. Furthermore, the locking member swings in a plane parallel with the surface of the barrel staves and it is adapted to be hooked between the body of the wire 3 and the outer surface of the barrel so that when the barrel is filled, the tension on the hoop or wire will frictionally hold the locking member 7 against the outer surface of the barrel and thus contribute to a great extent in preventing the locking member from being accidentally disengaged by contact with adjacent objects.

From the foregoing description, taken in connection with the accompanying drawing, the advantages of the construction and of the method of operation will be readily apparent.

to those skilled in the art to which the invention appertains, and while I have described the principle of operation of the invention, together with the apparatus which I now 5 consider to be the best embodiment thereof, I desire to have it understood that the apparatus shown is merely illustrative and that such changes may be made when desired, as are within the scope of the claims.

10 Having thus described the invention, what I claim is:—

1. A knockdown receptacle comprising a plurality of parts, a flexible member permanently attached to the parts for connecting 15 the latter together, loops formed at the ends of the member, and a locking device consisting of a metal piece disposed flatwise with respect to the outer surface of the receptacle and having an opening at one end for receiving 20 one of the loops for permanent connection therewith, a hook at the same end extending longitudinally for detachably receiving the hook at the free end of the member, and a laterally extending hook adjacent the 25 opposite end of the piece and bent over from one of the long edges of the latter for engaging over the member at a point inwardly from the detachable loop, the free end of the member extending the full length of the de- 30 vice and the detachable loop being shorter

than the device to permit the inner end of the loop to directly engage and press on the device to urge the latter in a direction to assist in maintaining the second hook in engagement with the member.

2. A knockdown receptacle comprising a plurality of parts, a fastener consisting of a wire to which the parts are attached, a locking device comprising a member to which one end of the wire is hingedly connected, a hook 40 at one corner of the member, a loop on the other end of the wire shorter than the length of the member and adapted to be placed over the corner for engagement with the hook, a laterally extending hook on the member under which the wire is engaged when the member is in locking position, the outer end of the loop engaging the first hook and the inner end of the loop being disposed between both hooks and bearing directly on the member at a point intermediate the ends thereof to exert a pressure on the latter in a direction to maintain the second hook in engagement with the wire. 45

50 In testimony whereof, I affix my signature 55 in presence of two witnesses.

CLINTON S. SHUGART.
